(57) **CLAIM**

The ornamental design for a skid steer loader, as shown and described.

DESCRIPTION

FIG. 1 is a perspective view of the skid steer loader showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarge view of circle labeled 9 in FIG. 1 thereof;

FIG. 10 is an enlarge view of circle labeled 10 in FIG. 1 thereof; and,

FIG. 11 is an enlarge view of circle labeled 11 in FIG. 2 thereof.

The long dash short dash broken lines shown on FIGS. 1, 2, and 9-11 are provided to define the enlargement regions in each and form no part of the claimed design.

1 Claim, 11 Drawing Sheets
